PHOTOGRAPHIC CAMERA

Frank A. Zagara, Pittsford, N.Y., assignor to Eastman Kodak Company, Rochester, N.Y., a corporation of New Jersey

Filed Feb. 14, 1963, Ser. No. 73,570

Term of patent 14 years

(Cl. D61—1)

FIG. 2

FIG. 4

FIG. 1

FIG. 5

FIG. 3

FIG. 6

FIG. 9

FIG. 7

FIG. 10

FIG. 8

FIG. 1 is a front view of a photographic camera showing my novel design with the flash holder retracted into the camera body;

FIG. 2 is a top plan view thereof;

FIG. 3 is the rear view thereof;

FIGS. 4 and 5 are elevational views of opposite ends thereof;

FIG. 6 is a bottom plan view thereof; and

FIGS. 7-10 correspond to FIGS. 1, 3, 4 and 5, respectively, but show the flash holder in an extended or operative position.

The broken-line showing of a flash lamp in FIG. 7 is for illustrative purposes only.

I claim:

The ornamental design for a photographic camera, as shown and described.
